[57] ABSTRACT

[21] Appl. No.: 82,943

A method and apparatus for continuously winding strand material on alternate ones of a pair of side-by-side takeup reels. The reels are selectively rotated, and each has a strand snagger plate. When one reel is full, the strand is moved by suitable means toward the other reel for winding thereon without interrupting the feeding of the strand. The strand is caught by the snagger plate on the empty reel during changeover. A finger member is provided for preventing the strand from being caught by the snagger plate on the full reel.

METHOD AND APPARATUS FOR STRAND WINDING AND REELING

BACKGROUND OF THE INVENTION

1. Field of the Invention

This invention relates to improvements in a method and apparatus for continuously winding strand material on alternate ones of a pair of rotary takeup reels.

More particularly, the invention relates to improvements in a method and apparatus for changing over the winding of a strand from a fully wound reel to an empty reel without interrupting the feeding of the strand during continuous winding and while minimizing the tendency of the strand to break during changeover.

2. Description of the Prior Art

Continuous strand winding and reeling apparatus generally comprises a pair of detachable, rotatable takeup reels which are mounted on a common axis of rotation, the reels slightly spaced apart from one another. Means are provided for rotating one of the reels to wind strand material, guided thereto by a distributor, while the other reel remains stationary. When the one reel has been wound with the desired amount of strand material, rotation of the other reel is begun, and the strand is then transferred by the distributor for winding from the fully wound reel to the empty reel and simultaneously cut. It is to be understood that the terms "fully wound reel" and "full reel" as used herein denote a reel which has been wound with a predetermined amount of strand material. To assist in transferring the strand from the full reel to the empty reel, a snagger plate having teeth for snagging the strand is detachably connected on the end of each reel facing the other reel. The strand is moved, into a position where it can be snagged or caught by the teeth, by the distributor when it moves from a position over the full reel to a position over the empty reel. With the strand extending between the two reels after the distributor has moved to this position, the teeth of the snagger plates catch the strand and direct it to a cutting knife located between the two reels to cut it. The snagger plates usually hold the cut ends of the strand until the winding of the strand on the empty reel is underway.

It is important during the transfer of the strand from the full reel to the empty reel to minimize the strain exerted on the strand when it is caught by the snagger plates so as to avoid breaking it. In order to minimize the strain, attempts have been made to place the strand in a position where it extends from the distributor, when the distributor is moved over to the empty reel, in a direction extending substantially tangentially to the cylindrical surface of the empty reel at the time it is snagged by the snagger plates for cutting.

If the strand is in the above-described position when caught by a tooth of the snagger plate, the strain imparted on the strand is minimized since the tooth has a component of velocity, in the direction of strand travel, which is substantially equal to the velocity of the strand.

If the strand is not in the above-described position when caught by a tooth of the snagger plate, the tooth generally has a component of velocity, in the direction of strand travel, which is greater than the speed of the strand. The tooth thus can jerk the strand when catching it, thus possibly breaking it.

Apparatus for attempting to place the strand in the aforesaid preferred snagging position, where it extends from the distributor tangentially to the cylindrical surface of the empty reel, is known. The apparatus includes guides extending over a portion of the periphery of the snagger plates for guiding the strand to the theoretical preferred position during changeover while preventing the snagger teeth from catching the strand during movement to this position. A swinging bar is also provided between the reels and the guides for positively moving the strand over the guides down toward the preferred snagging position. An example of the above-described apparatus is shown, for example, in Canadian Pat. 643,357, issued June 19, 1962, Judson N. Detrick, inventor.

It has been found, however, that this type of apparatus still does not avoid placing undue strain on the strand when it is snagged. Even with suitable guide means for guiding the strand, extending between the reels, down to a theoretically preferred snagging position, the strand is caught first by the full reel snagger plate. When caught by the full reel snagger plate, the strand actually extends in substantially the same direction as the direction the tooth of the full reel snagger plate is travelling. The full reel snagger tooth moves at a higher speed than the speed of travel of the strand. Thus, the tooth, when catching the strand as it extends in substantially the same direction as the direction the tooth is moving, places a load on the strand, which could lead to its breaking.

SUMMARY OF THE INVENTION

The present invention is designed to overcome the above problem. The present invention ensures that the strand, during its transfer from the full reel to the empty reel, is snagged by the empty reel snagger plate rather than the full reel snagger plate when the strand has been moved to a position where it extends substantially tangentially to the cylindrical surface of the empty reel from the strand distributor means during changeover. When the strand, in this position, is caught by the empty reel snagger plate, the speed imparted on the strand by the engaging tooth, in the direction of the strand, is substantially equal to the speed of the strand itself. Consequently, the speed of advancement of the strand is substantially constant during the entire changeover operation, and there is substantially no stretching force imparted to the strand during the changeover operation.

The invention is directed toward a method for continuously winding a strand on alternate ones of a pair of rotary side-by-side takeup reels. Each reel has a snagger plate. A distributor guides strand material to the reels and is movable from a guiding position opposite to one reel to a guiding position opposite to the other reel. The method includes continuously winding the strand, guided from the distributor, on one of the reels; moving the distributor toward the other empty reel when the said one reel becomes full; guiding the strand extending from the full reel to the distributor, as the distributor is moved toward the other reel, toward a position where the strand extends from the distributor in a direction substantially tangential to the strand receiving surface of the other reel; means being actuated to prevent snagging of the strand in said position

by the full reel snagger plate; and snagging said strand, while in said position, by the snagger plate on the empty reel.

The invention is further directed toward an apparatus for continuously winding a strand on alternate ones of a pair of side-by-side takeup reels, each reel having a cylindrical surface for receiving strand material to be wound thereon and each reel having a snagger plate connected to its end facing the other reel. The apparatus includes means for selectively rotating the reels, a distributor for delivering strand material onto the reels, means for moving the distributor from a full reel position opposite to one reel to an empty reel position opposite to the other reel while it continues to deliver strand material to be wound on the full reel, means for guiding the strand material during the movement of the distributor to the empty reel position toward a position where it extends from the distributor in a direction substantially tangential to the cylindrical surface of the empty reel, and means, movable to cooperate with the guide means, to prevent the snagger plate on the full reel from engaging the strand when moved to said position while permitting the snagger plate on the empty reel to engage the strand when in said position.

BRIEF DESCRIPTION OF THE DRAWINGS

The invention will now be described in detail having reference to the accompanying drawings, wherein:

FIG. 1 is a front elevation view of strand winding and reeling apparatus for carrying out the invention showing the position of the strand at the beginning of the changeover operation;

FIG. 2 is a side elevation view in partial cross-section, showing the position of the strand immediately before being snagged by the empty reel snagger plate;

FIG. 2A is a schematic view showing the forces involved when the strand is snagged when in the position shown in FIG. 2;

FIG. 3 is a schematic view showing the position of the strand when caught by the full reel snagger plate as in prior art;

FIG. 4 is a partial side elevation view showing the means for preventing the snagging of the strand by the full reel snagger plate;

FIG. 5 is a partial bottom elevation view showing the position of the means for preventing the snagging of the strand by the full reel snagger plate;

FIGS. 6A, 6B and 6C are details of another embodiment for preventing snagging of the strand by the full reel snagger plate; and

FIGS. 7A, 7B and 7C are details of a further embodiment for preventing snagging of the strand by the full reel snagger plate.

DESCRIPTION OF THE PREFERRED EMBODIMENTS

As shown in FIG. 1, the apparatus 1 for continuously winding a strand 3 on alternate ones of a pair of side-by-side rotary takeup reels 5, 5' includes a frame 9 supporting the first and second reels 5, 5' for rotation about a common axis. Driving and braking means 11, 13 supported by the frame are connected to the reels 5, 5' respectively. Mounted on top of the frame 9 is a distributor 15 having outlet guides 16 for guiding the

strand from a supply source (not shown) to the takeup reels for winding thereon. The distributor 15 is mounted for movement in a direction parallel to the axis of rotation of the reels along guide means 17 supported by the frame 9. The distributor can be moved between a first position A opposite to the first reel 5 to a second position A' opposite to the second reel 5', as shown in FIG. 1, so that it may guide strand material to be wound to either of the reels depending upon which position it is in. Suitable means (not shown) are provided for moving the distributor between the first and second positions and also for moving the distributor at each of the first and second positions so that it traverses a cylindrical strand receiving surface 19, 19' of each of the reels located between reel flanges 21 and 23 and 21' and 23' respectively.

Shortly before movement of the distributor between its positions A and A' and before strand changeover, the empty reel 5' is given a rotational speed ω by its drive means 13 so that the peripheral speed of its strand receiving surface 19' is substantially equal to the strand speed V_s . The full reel 5, on the other hand, has a rotational speed of ω' to take into account the difference in speed necessary to have the peripheral speed of the outer diameter of the strand core, already wound on the reel, equal to the strand speed V_s .

A snagger plate 25, 25' is mounted adjacent the inner flange 21 and 21' of each of the reels 5, 5' and 30 has teeth 27, 27' extending about its periphery facing in the direction of rotation of each reel for snagging the strand when the strand is placed into a snagging position during movement of the distributor between its first and second positions. The diameter of each 35 snagger plate is equal to or slightly greater than the diameter of the flanges of the reels.

In order to prevent the snagger plates 25, 25' from catching the strand immediately when the strand is moved across the snagger plates during movement of the distributor 15 between the first and second positions A, A', guide means 28, 28', suitably connected to the frame 9, extend over a portion of the periphery of each snagger plate 25, 25', as partially shown in FIG. 2. 40 Each guide means includes a curved plate 29, 29' extending over a portion of the periphery of the snagger plates and being wide enough to cover the teeth on the snagger plates. One end 31, 31' of each guide plate 29, 29' is located rearwardly of a first point B on the 45 periphery of each snagger plate 25, 25'. Point B is located by the intersection of an imaginary plane C, drawn from the outlet guides 16 of the distributor 15 to extend tangentially to the cylindrical surface 19' of the reel 5', with the outer periphery of the snagger plates. The other end 33, 33' of each guide plate 29, 29' terminates adjacent point D at the bottom of each snagger plate where said imaginary plane C again intersects the periphery of each snagger plate on the side of the cylindrical surface 19' remote from the distributor 15. This 50 second point D is at the preferred position for locating the strand 3 for catching it by the empty reel snagger plate tooth 27' during transfer of the strand from the full reel to the empty reel.

In order to assist in moving the strand 3 over the guide plates 29, 29' down to the preferred transfer position D, a pusher rod 35 is mounted between the two reels and the guide plates on a collar 37 mounted

on a shaft 39 located at the axis of rotation of the reels. The rod 35 extends from the collar radially outwardly a greater distance than the radial distance of the guide plates 29, 29' from the axis of rotation of the reels. The pusher rod 35 is movable from a first inoperative position located to the rear of point B to a second position at the lower end 33, 33' of the guide plates 29, 29', as shown in dotted lines in FIG. 2. Suitable means 50, for rotating the collar 37 and thus rod 35 about shaft 39 between its positions, are provided. As shown in FIG. 2, the collar rotating means 50 can comprise suitable actuating means, such as a hydraulic cylinder 52, pivotably connected at one end to the frame 9. The actuating rod 53 of the cylinder 52 is pivotably connected to one arm 54 of a bellcrank 55 which is pivotably mounted by a pin 56 to the frame 9. The other arm 57 of the bellcrank is pivotably connected to one end of a curved drive arm 58, the other end of which is pivotably connected to a projection 59 on the collar 37. The arm 58 is curved so as to be able to clear shaft 39 when moved by the actuating means to rotate the collar 37. During strand changeover, the rod 35 is moved to the second position by actuating cylinder 52 to withdraw rod 53 and thus pivot bellcrank 55 clockwise about pin 56, as viewed in FIG. 2. This causes drive arm 57 to rotate the collar 37 counterclockwise and thus rod 35 to the positions shown by dotted lines in FIG. 2. As the rod 35 is moved to its operative position, it intercepts the strand 3 extending between the full reel 5 and the distributor 15 as the distributor is moved from its first position A to its second position A'. The rod 35 carries the strand down around the outside of the periphery of the reels over the guide plates 29, 29' toward the transfer position D. Once the strand has been moved by the rod 35 over a portion of the periphery of the guide plates 29, 29' to a position approximately shown at E in FIG. 2, the strand proceeds down the remainder of the length of the guide plates on its own to position D, being pulled along by the rotating full reel.

If the full reel snagger plate 25 were allowed to engage the strand 3 as it left the end 33 of the full reel guide plate 29 at position D upon continued movement, the strand, when caught, would extend from the outermost strand layer on the full reel to the snagger plate, and from the snagger plate to rod 35 along the line "F" which is in a direction substantially the same as the direction of movement of the snagger tooth 27, as shown by arrow "G" at position "D" in FIG. 3. The standard equation for the linear velocity v a particle moving in a circular path of diameter d and having an angular velocity ω is given by $v = \omega d/2$. It follows therefore, that the linear speed V_2 of the strand along line "F" is equal to $\omega'(d/2)$ where ω' is the speed of rotation of the full reel and d is the diameter of the coil of strand wound on the reel. The linear speed V_a of the snagger tooth 27, along line "G" at position "D," is equal to $\omega'(d'/2)$ where d' is the diameter of the snagger plate. Thus, the speed of the tooth is greater than the speed of the strand by the ratio (d'/d) . The tooth thus jerks the strand when catching it as it leaves the guide plate, and this could break the strand.

If, on the other hand, the strand is caught by the empty reel snagger plate 25' at position D as shown in FIGS. 2 and 2A, the tooth 27', now travelling at a linear

speed of V_b , has a component of linear speed V_c in the same direction as the direction of strand travel. This component of linear speed V_c is equal to the strand speed V_s . This follows since the empty reel is rotated at a speed ω to have the speed of the drum surface 19' equal to the strand speed V_s . Thus, the speed of strand $v_s = \omega d''/2$ where d'' is the diameter of the drum.

The speed V_b of the tooth 27' of the empty reel snagger plate equals $\omega d''/2$ where d'' is the diameter of the empty reel snagger plate. Now, since V_c equals $V_b \sin \theta$ and since $\sin \theta$ equals (d''/d') , V_c must equal $V_b (d''/d')$ which is equal to $(d'/2) (\omega d''/d')$ which is equal to V_s . Thus, it is seen that the tooth 27' has a component of speed, V_c , in the direction of strand travel, which is equal to the strand speed V_s . Therefore, the tooth 27', when catching the strand, places little or no strain on the strand extending from the tooth to the distributor.

In order to prevent the strand from being caught by the full reel snagger plate, guide extensions 41, 41' are provided for selective cooperation with respective guide plates 29, 29'. As shown in FIGS. 2, 4 and 5, guide extension 41 can comprise a finger member 43 having a free leading end 45 which can abut with the trailing end 33 of guide plate 29 at position D. Member 43 cooperates with the guide plate 29 when abutted thereagainst to form a continuation of the guide means. The finger member 43 extends for a relatively short distance as compared to the length of the curved guide plate and has a strand guide surface 44 which has substantially the same curvature as the strand guide surface 46 of plate 29. The other end of the finger member 43 opposite its end 45 is connected to a support member 47. The support member 47 extends in the opposite direction to the finger member and is pivotably connected by a pin 48 to a portion of the frame 9. Hydraulic means 49, or other suitable means, are pivotably mounted on frame 9 and a rod 50 extending from the hydraulic means is pivotably connected to the end of member 47. Operation of the hydraulic means 49 moves member 47 and thus finger 43 about pin 48 from an initial position, shown in full lines in FIG. 4, where the end 45 of the finger 43 is spaced from the end 33 of the guide plate 29, to a final position shown in dotted lines, where the end 45 of finger member 43 abuts the end 33 of the plate 29 to form a continuation of the strand guide surface 46 of guide plate 29.

Guide extension 41' is identical in construction to extension 41 and cooperates with guide plate 29' in the same manner as extension 41 cooperates with guide plate 29.

Preferably, the ends 33, 33' of the guide plates and the free ends 45, 45' of the finger members extend at an angle to the rotational axis of the reels, as shown in FIG. 5. The angle α is selected to approximately match the path taken by the strand during changeover between the reels after the strand has been moved by the rod 35. The ends 33, 45 extend at an equal but opposite angle to the ends 33', 45' to accommodate the strand direction during changeover from reel 5' to reel 5.

In operation, the distributor 15 begins to move from position A opposite to the now nearly full reel 5 to position A' opposite to the empty reel 5'. Suitable control means are provided to initiate operation of the hydrau-

lic means 49, preferably through movement of the distributor toward position A', to move finger 43 from initial position, shown in full lines in FIG. 4, to the final position, shown in dotted lines, where it forms an extension of the guide plate 29. Finger 43' remains in the initial position with its free end 45' spaced from trailing end 33' of guide plate 29' to form a gap 51', as shown in FIG. 5. The free end face 45' is in position to form a stop surface for the strand, thus preventing the strand from moving past the gap 51' without dropping through it.

As distributor 15 nears position A', hydraulic cylinder 52 is actuated to move pusher rod 35 from its first position rearwardly of point B to a position near point D as shown in FIG. 2, thus guiding the strand, now extending across the guide plates 29, 29', down around their guiding surface 46 toward position D. As the rod 35 moves past point E, the strand continues to move over the guide plates and leaves guide plate 29 at 20 position D to continue its travel on finger 43 thus preventing the full reel snagger plate from catching it. The strand continues movement to the end of guide plate 29' assisted, if necessary, by continued movement of the rod 35 toward point D, and here it drops through gap 51' to be caught by a tooth 27' on the empty reel snagger plate 25' in the proper position to minimize strain. The strand usually is caught by the empty reel snagger plate before it reaches support 47, although it may also dwell at the base of the V formed by members 43 and 47, and is then cut by a knife 53 positioned between the reels as is well known.

The free end of the strand is wrapped about the full reel and the other end of the strand, caught by the 35 snagger tooth on the empty reel snagger plate 25' is wrapped about the surface 19' of the empty reel 5' to commence winding thereon with the distributor now located opposite to the empty reel. The finger 43 and the rod 35 can now be returned to their initial (or at 40 rest) positions automatically, if desired.

FIGS. 6A, 6B and 6C illustrate a second embodiment of the invention for ensuring that the strand is caught first by the snagger plate associated with the empty reel. In this embodiment, each guide plate 29, 29' is constructed to each have a curved extension plate 61, mounted in their lower end. The curved extension plate 61 can be selectively moved from a position located within and adjacent the guide plate 29, as shown in FIG. 6A, where it is located to the rear of edge 33 of the guide plate 29, to a position where it extends past the edge 33 of the guide plate 29, as shown in FIG. 6B. In this position, it forms a continuation of the guide plate 29, thereby preventing the strand 3, as it leaves 55 plate 29, from being engaged by the tooth 27 of the full reel snagger plate 25. The plate 61 associated with each guide plate is moved selectively in the same manner as the fingers 41, 41' to ensure snagging of the strand by the empty reel snagger plate with the strand in the 60 preferred position. The plates 61 are mounted to the guide plates by guide means 63. A bowden cable 65, or other suitable means, extending in a conduit 67, and connected at one end to suitable moving means (not shown) mounted on the frame, is connected to each extension plate to move it to the operative position shown in FIG. 6B during changeover.

A further embodiment of the invention is shown in FIGS. 7A, 7B and 7C. In this embodiment, guide members 81, 83 are mounted in a position between the reels. Each guide member 81, 83 includes a guide plate extension 85 having the same curvature as the guide plates 29, 29'. The guide plate extension 85 is mounted on a pivoted arm 87. The arm 87 is mounted on a pivot 89 which in turn is fixed on a center post 91 located between the reels. The arm 87 has an extension 93, the free end of which is connected to a moving means 95, such as a hydraulic cylinder, for example. The moving means can also be mounted on a center post 91. Each extension 85 is normally in the position shown in FIG. 7A. When strand changeover from one reel to the other is to occur, the appropriate arm 87 is pivoted by the moving means 95 to move one of the extensions to the position shown in FIG. 7B to prevent the strand from being caught first by the full reel snagger plate 25.

I claim:

1. A method of continuous strand reeling on a pair of rotary take-up reels, each reel associated with a snagger plate, comprising the steps of:

winding the strand on one of said reels from a distributor,

moving the distributor from a guiding position opposite to the one reel to a guiding position opposite to the other reel when said one reel contains a predetermined amount of strand material, guiding the strand, extending from the one reel to the distributor as the distributor is moved toward the other reel, to a position where the strand extends from the distributor in a plane substantially tangential to the strand receiving surface of the other reel,

preventing the strand in said position from being snagged by the snagger plate associated with the reel containing the predetermined amount of strand material, and

snagging said strand while in said position by the empty reel snagger plate.

2. A method as claimed in claim 1, including the step of cutting the strand when it has been caught by the empty reel snagger plate.

3. An apparatus for continuously winding a strand on alternate ones of a pair of side-by-side take-up reels, each reel having a cylindrical surface for receiving strand material to be wound thereon and each reel associated with a snagger plate connected to its end facing the other reel, said apparatus comprising:

means for selectively rotating said reels,

means for moving the distributor from a full reel position opposite to one reel to an empty reel position opposite to the other reel while it continues to deliver strand material to be wound on the one reel,

means for guiding the strand material, during the movement of the distributor to the empty reel position, toward a position where the strand extends from the distributor in a plane substantially tangential to the cylindrical surface of the empty reel, and

means movable to cooperate with the guide means, to prevent the snagger plate on the full reel from engaging the strand when moved to said position, and to allow engaging said strand, while in said position, by the empty reel snagger plate.

4. An apparatus as claimed in claim 3, wherein said guide means includes a guide plate covering a peripheral portion of each snagger plate, each guide plate terminating in an end edge at a position determined by where an imaginary plane, extending from the distributor tangentially to the cylindrical strand receiving surface, intersects the periphery of the snagger plate on the side of the cylindrical strand receiving surface remote from said distributor.

5. An apparatus as claimed in claim 4, wherein said means, movable to prevent the snagger plate on the full reel from snagging the strand, comprises a member movable from a position spaced from the end edge of the guide plate to an operative position to form a continuation of the guide plate.

6. An apparatus as claimed in claim 5, wherein said member comprises a finger having a free end edge, and means moving the finger to the operative position where its free end edge abuts the end edge of the guide plate.

7. An apparatus as claimed in claim 6, including means pivotably mounting the finger for movement to the operative position.

8. An apparatus as claimed in claim 5, wherein the member comprises a plate member, means mounting the plate member on the guide plate adjacent the end edge, and means moving the plate member relative to the guide plate so it extends past the end edge of the guide plate.

10 9. An apparatus as claimed in claim 6, wherein the end edge of the guide plate and the end edge of the finger extend at an angle to the axis of rotation of the reels.

10 10. An apparatus as claimed in claim 3, wherein said means for guiding the strand includes a guide rod located between the reels, an axial shaft extending between the reels, a member rotatably mounted on said shaft, said rod mounted on said member, and means for rotating said member on said shaft to move said rod.
